FALSE TWISTER

Hans Alwin Schrenk, Arnhem, Netherlands, assignor to American Enka Corporation, Enka, N. C., a corporation of Delaware

Application April 9, 1956, Serial No. 576,971

Claims priority, application Netherlands April 21, 1955

5 Claims. (Cl. 57—77.3)

This invention relates to false twisting apparatus and more particularly to an improved false twister for imparting superior curl to thermoplastic yarns.

In the art of curling thermoplastic yarns and threads, it is known to interpose a false twister between two twist stops and to impart curl to the yarn in its run from one twist stop to the false twister and to take the curl out again in the run of the yarn from the false twister to the other twist stop. While the curl is in the yarn, it is set by successive heating and cooling steps. In general, the linear speed at which the process may be conducted is related to the speed at which the false twister may be run. Thus a good deal of work has been done in an effort to produce reliable false twisters capable of high speed operation.

One of the more successful false twisters is made by providing a rotatable body having opposite end portions provided with yarn channels and a narrow intermediate waist between the end portions. In this type of apparatus the yarn is led into one end portion at the axis of rotation, through the channel which diverges from the axis of rotation, around the waist where the yarn slips, and into the channel of the other end portion which converges toward the axis of rotation where the yarn emerges again.

It is an object of the present invention to improve on the foregoing type of false twister and more particularly to prevent relative slippage between the yarn and the waist thereof whereby stronger false twist may be imparted to the yarn with resulting improvement in curl.

It is proposed according to the present invention to provide a false twister having end portions provided with yarn channels, said end portions being interconnected for rotation together and a waist portion between said end portions that is freely rotatable in relation to and coaxially with the end portions.

Other objects and advantages of the invention will be apparent upon the consideration of the following detailed description of a preferred embodiment thereof in conjunction with the annexed drawings, wherein:

Figure 1 is a perspective view of a false twister constructed in accordance with the teachings of the present invention;

Figure 2 is a diametrical view in vertical section through the false twister of Figure 1; and

Figure 3 is a sectional view, somewhat enlarged, showing the preferred construction of one of the elements of the present invention.

Referring now in detail to the drawing, the false twister consists of a rotatable body 10 having an upper frusto-conical end portion 11 and a lower end portion 12 which is really a thick flange at the upper end of a driving sheave 13 for receiving a belt, not shown, for rotating the body 10. The end portions 11 and 12 are interconnected by a stud 14 which projects from the end portion 12 and which is threaded into the center of the base of the frusto-conical end portion 11. A stationary body 15 supports centrally therein a yarn tube 16. Ball bear-

ing races 17 and 18 are mounted about the upper end of the tube 16 and the body 10 is mounted for free rotation on these bearings.

Within the flange or lower end portion 12 there is a diagonal channel 19 leading from a port 20 which is coaxial with the tube 16 to a port 21 which is radially offset from the axis of the end portion 12 and the tube 16. The end portion 11 is provided with a port at 22 which is radially offset in respect of the axis of rotation of the body 10 and this port is connected by a channel 23 to a port 24 at the top of the end portion 11, this port being coaxial with the center line of the tube 16. For convenience in threading up, the number of channels in the end portions 12 and 11 may be in excess of one, two being shown in the embodiment of the invention depicted in Figures 1 and 2.

Surrounding the stud or pin 14 which acts as a connecting neck between end portions 11 and 12 there is a collar 25. This collar is mounted on the neck for free rotation by any friction-free arrangement known to the art. While the collar 25 is shown in Figure 2 as being generally cylindrical, it is preferable to have its outside surface somewhat concave in relation to the axis of rotation. In other words, it is preferred that the external surface of the collar be of somewhat smaller diameter in the middle of the length than it is at the end, as shown more clearly at collar 25a in Figure 3.

In use, the false twister of the present invention is supplied with thread coming in the direction of the arrow from a twist stop not shown. The yarn or thread passes through the tube 16 and through the channel 19. It is then wrapped around the collar 25 which is mounted for free rotation about the pin 14. After wrapping at least 360° around collar 25, and preferably 720°, the thread is led through the channel 23 and out of the false twister in the direction of the arrow to an upper twist stop not shown. The body 10 of the false twister is rotated by a belt frictionally engaging the sheave 13. While end portions 11 and 12 and connecting pin 14 rotate as a unit, the collar 25 is freely movable in relation to the body 10 and its movement is controlled by the yarn rather than by the action of the sheave.

It is believed that the good results achieved by the present invention may be attributed to the fact that the collar 25 keeps the thread from sliding longitudinally in its movement from the lower end portion 12 of the body 10 to the upper end portion 11 thereof. It is noted that because of the use of the collar 25, rotation of the thread about its own axis in its run between the ports 21 and 22 is reduced. In view of the fact that the thread does not appreciably move lengthwise or about its axis while in contact with the collar 25, the angle of wrap around the pin 14 can be increased without appreciable influence on thread tension. This has been found to improve the reliability of the false twister. The external concavity of the surface of the collar 25 helps to cause the thread windings, if they exceed 360°, to arrange themselves side by side. Because of the tensions which are possible with this type of apparatus, the ballooning which is common with this type of false twister is avoided.

Further the end portion of the false twisting device may have a construction different from that shown in the figures. For instance, the channels in the said portions may extend parallel to the vertical center line thereof or may diverge from the freely rotatable collar. Neither is it necessary for these channels to terminate at the bottom side of the end portion but they may end at the side of this element. In that case, however, it is desirable to round off the bottom edge of the end portion in order to facilitate the sliding of the thread over this edge. Finally the channels need not be duplicated in twofold

in the end portions, although this is preferred with a view to obtaining a quiet rotation of the spindle.

What is claimed is:

1. A false twister comprising a body including two end portions and an intermediate neck interconnecting them, said portions having yarn channels extending lengthwise therethrough, means mounting said body for rotation and a collar freely rotatable co-axially about said neck.

2. A false twister comprising a stationary tube, a body including two end portions interconnected by a narrow neck, said end portions each having a yarn channel therethrough, means mounting said body for rotation about said tube with one end of one of said channels in registry with the end of said tube and a collar freely rotatable co-axially about said neck.

3. A false twister comprising a stationary tube, a body including two end portions interconnected by a narrow neck, a collar surrounding said neck and freely rotatable with respect thereto, means mounting one of said end portions for free rotation coaxially about said tube, each end portion having a yarn channel extending lengthwise therethrough, the channels being at their ends adjacent the collar further from the axis than at their other ends.

4. A false twister comprising a body including two end portions and an intermediate neck interconnecting them, said portions having yarn channels extending lengthwise

therethrough, means mounting said body for rotation and an externally concave collar freely rotatable co-axially about said neck.

5. A false twister comprising a stationary tube, a body including two end portions interconnected by a narrow neck, a collar surrounding said neck and freely rotatable with respect thereto, means mounting said body for free rotation about said tube, each end portion having therein a yarn channel extending in converging relation to the axis of rotation of the body from the end adjacent the neck, the channels being at their ends adjacent the collar radially further from the axis than said collar and at their other ends being coaxial with the axis of rotation of the body.
